UNITED STATES PATENT OFFICE.

HERVEY E. BUTCHER, OF BUFFALO, NEW YORK.

REINFORCED-CONCRETE COLUMN.

1,410,453.

Specification of Letters Patent. Patented Mar. 21, 1922.

Application filed June 5, 1919. Serial No. 301,862.

To all whom it may concern:

Be it known that I, HERVEY E. BUTCHER, a citizen of the United States, and a resident of the city of Buffalo, in the county 5 of Erie and State of New York, have invented a new and useful Improvement in Vertical Reinforced-Concrete Structural Members, and Particularly in Reinforced-Concrete Columns, of which the following 10 is a specification.

My invention relates principally to reinforced concrete columns. Heretofore, it has been common to embed hoops or spirals in reinforced concrete columns for the purpose 15 of taking care of the shearing or diagonal tensile stresses; but such hoops and spirals are subject to numerous disadvantages which it is the object of the present invention to avoid. In the first place, 20 the successive hoops or turns of the spiral are spaced apart leaving intervening spaces without circumferential reinforcement. Secondly, such hoops or spirals are likely to become to a greater or less extent, distorted 25 or dislocated in the course of actual construction. Thirdly, the hoops or spirals themselves in their action in resisting the lateral pressure brought upon them, due to a vertical load on the column, become in 30 reality cutting edges because of their intermittent concentration and thereby create shearing planes, the very thing they are intended to obviate. Again, in the practical use of such hoops or spirals, temporary 35 forms are required for molding the concrete.

One object of the present invention is to so design the circumferential reinforcement that it will also serve as a mold and thereby make it practicable to dispense with the 40 temporary false work heretofore used in the erection of reinforced concrete columns. Another object is to produce a favorable 45 keying surface on the column reinforcement for receiving a covering of fire-proofing material.

The invention consists principally in a tubular metal shell filled with concrete and designed so as to be capable of resisting the shearing or diagonal tensile stresses in the 50 column. The metal shell may by means of slits, reticulations or deformations, be made to form a mechanical bond with the concrete without material loss in the tensile strength of the shell circumferentially and 55 by the same operation its exterior face be made to produce a favorable keying surface

for receiving a covering of plastic material that will serve to fire-proof the column. The invention also consists in the process of making columns hereinafter described and 60 claimed. It also consists in the parts and arrangements of parts hereinafter described and claimed.

In the accompanying drawing, wherein like reference numerals refer to like parts 65 wherever they occur,

Fig. 1 is a vertical longitudinal section taken through a concrete column showing a tubular metal shell embodying my invention in connection therewith, the lower portion 70 of the shell being shown in side elevation;

Fig. 2 is a horizontal section through the column, the section being taken through one of the rows of pockets on the line 2—2 in 75 Fig. 1;

Fig. 3 is an enlarged face view of a portion of a flat sheet of metal before being rolled into the form of a shell with the slits 80 formed therein;

Fig. 4 is a section on the line 4—4 in Fig. 3;

Fig. 5 is a section on the line 5—5 in Fig. 3;

Fig. 6 is a vertical section taken through 85 one of the pockets, a portion of the concrete filling and fireproof covering being shown; and

Fig. 7 is a fragmentary horizontal section taken through the pockets adjacent to one 90 of the reinforcing rods showing a means for securing the rods in position.

The column comprises a tubular shell 1 of sheet metal filled with concrete 2. The shell is provided throughout its surface with a 95 multiplicity of slits 3, the slits being arranged in rows and the slits in each row being preferably staggered with respect to the slits of the next adjacent rows. Preferably also, the lower lip of each slit is displaced 100 outwardly thereby forming a kind of cup or pocket 4 which projects beyond the normal cylindrical surface of the shell. In practice, it is preferable to slit the sheet in the flat and afterwards roll it into the form of a 105 shell and fasten its ends together either by riveting or by lap-welding or butt-welding them. As the shell is intended to contribute tensile strength to resist the outward pressure of the concrete, it should be made in 110 the form of a continuous circular shell as distinguished from a longitudinally fluted

or corrugated shell and from a sheet that is rolled into the form of a cylinder without having its ends firmly fastened together. As the joint or seam is liable to be weaker in tensile strength than the body of the unslotted sheet, the strength of the joint or seam fixes the limit of strength of the shell; and consequently some departure from horizontality of slits is permissible. It is estimated that the joint or seam may develop about ninety-five per cent (95%) of the strength of the solid shell or of the shell with horizontal slits. This five per cent (5%) loss of efficiency would mean that the slits might be inclined with the horizontal as much as eighteen per cent (18%) without injury to the tensile strength of the shell as a whole.

When the column is to have a flaring head, the upper end 5 of the reenforcing shell 1 is made of conical or pyramidal form. The upper end 5 is shown in the drawings as being made separate from the cylindrical portion of the shell and as having a tubular extension 6 at its lower end arranged to fit into the upper end of the cylindrical portion of the shell. The conical portion of the shell is made of sheet metal rolled to shape and having its ends welded or otherwise secured so as to make the shell capable of resisting circumferential tension.

In constructing the column, the metal shell is first set in its proper position and held in place by any suitable means, the cups on the outer surface thereof being open toward the top. If vertical reenforcing rods are used, such rods 7 are properly positioned inside of the metal shell, and secured in position with reference to the shell either before the shell itself is positioned or afterwards, according to convenience. The rods 7 are preferably secured in the shell by wire loops 8 which pass around the rods and through the slits 3, small spacing blocks 10 intervening between the shell and the rods to insure the proper embedment of the rods in the concrete. When the metal shell is properly positioned, concrete in plastic or semi-plastic condition is poured into the top thereof and suitably tamped. In this way, the concrete is made to fill the entire space inside of the shell and thereby embeds the reenforcing bars. At the same time, the concrete is caused to flow into the pockets on the outer surface of the shell and forms a mechanical bond with it. On account of the concrete being viscous, the portion that flows into a cup does not assume a horizontal level on top; but on the contrary the top thereof inclines downwardly and outwardly from the upper lip of the slit that serves to form such cup. Thus, the top of the concrete in the cup is lower than the top edge of the cup itself and consequently there is little or no loss of the concrete by leakage over the top edge of the cup. At the same

time, the unfilled portion of the cup in connection with the radial projection of the wall of the cup, taken in connection with the multiplicity of similar arrangements throughout the surface of the shell, affords an excellent bonding or keying surface for a fire-proof covering. This covering, preferably cement plaster, is applied in one or more layers of sufficient thickness to afford a substantially fire-proof coat 9 or protection for the column.

Heretofore, it has been impracticable for economical reasons to make reenforced concrete columns with the entasis desired for architectural effect; and it is an advantage of my invention that this desired entasis can be economically obtained.

It is noted that by reason of the mechanical bonding of the concrete core with the slotted shell, the shell is made to function as vertical reenforcement as well as circumferential reenforcement: that is to say, by reason of such mechanical bonding or interlocking of the metal shell with the concrete core, the metal materially increases the strength of the column for resisting vertical stresses as well as for resisting those circumferential stresses that have heretofore been resisted by spirals and hoops. And it is further noted that while the shell performs the functions of the hoop and spiral reenforcements heretofore used, it does so much more efficiently by reason of the fact that the continuity of the shell distributes the metal uniformly through the entire length of the column as compared with the intermittent concentration of the reinforcement occasioned by the spacing of the spirals and hoops.

It is further noted that the danger of the metal shell becoming distorted or dislocated in the construction work is minimized and therefore its use assures erection of the column in accordance with design.

It is further noted that the slitting of the shell need not reduce the capacity of the shell to resist circumferential tensile stress even though the slits are inclined with a plane at right angles to the axis of the shell; provided that the strength of the shell multiplied by the cosine of the angle of inclination of the slits is not less than the strength of the joint.

It is further noted that the use of the metal shell eliminates the necessity for the temporary form work heretofore used in the construction of reenforced concrete columns.

It is further noted that, even after the pocket forming lips of the slit are separated, they continue throughout their length at substantially the same horizontal height so that there is no such tendency for the plastic material to run out as there would be with openings wherein the upper lip is located materially above the lower lip or wherein one end of the opening is materially lower

than the other. With the limitations noted, it is obvious that the pockets may be formed otherwise than as specifically described without risk of losing any of the plastic material; 5 for instance, the upper lip may be displaced inwardly, leaving the lower lip in its original position or displaced outwardly as desired. In such case, the inwardly projecting lip may be made to position the vertical reen- 10 forcing bars further inwardly from the normal surface of the cylindrical shell. Obviously also there need be no slits or perforations in the shell and the slits or perforations in the shell need not be substantially hori- 15 zontal to come within my invention, so long as the shell has sufficient strength to resist the lateral pressure transmitted to it by the concrete.

What I claim is:

20 1. A column comprising a sheet of metal whose ends are brought together and firmly secured to form a shell that has a continuously convex exterior surface and is capable of resisting circumferential tension and has upwardly and outwardly opening cup 25 shaped openings adapted to constitute a keying surface, a filling of concrete in said shell and a fire-proofing coating surrounding said shell whereby said shell serves as a form for the concrete and as a reinforcement therefor and affords a keying surface for the fire- 30 proofing coating.

2. A reenforced concrete column comprising a circumferentially continuous metal shell having substantially horizontal slits therein, either the upper or lower of the lips of said slits inclining so that the lower edges of the upper lips are offset inwardly with respect to the upper edges of 35 the lower lips and a core of concrete interlocking with said shell.

3. A reenforced concrete column comprising a metal shell having substantially horizontal slits therein, the lips of said slits being integral with the shell except along the slit and the one free edge of each lip being offset radially of the column with respect to the free edge of the other lip of said slit so as to form an upwardly opening pocket that 40 will retain the flowing concrete and provides a bonding key for a subsequent coating, a core of concrete interlocking with said shell and a coat surrounding said shell and keyed thereto.

45 4. A reenforced concrete column comprising a tubular metal shell and a concrete core, said shell having substantially horizontal slits therein, the lower lip of each slit being integral with the shell at its ends and base and inclining upwardly and outwardly to form a bonding pocket which will retain the flowing concrete and provide a key for a subsequent coating.

50 5. A reenforced concrete column comprising a tubular metal shell flaring at the end

and a concrete core, said shell having horizontal slits therein and the lower lip of each slit being integral with the shell at its ends and base and inclining upwardly and outwardly to form a bonding pocket which will 70 retain the flowing concrete and provide a key for a subsequent coating.

6. A reenforced concrete column comprising a circumferentially continuous metal shell, a concrete core filling and interlocking 75 therewith, and a coating surrounding said shell, said shell having horizontally elongated slits therein, some of the lips of said slits having an upward and outward inclination whereby the lower edges of the upper 80 lips are positioned inwardly with respect to the upper edges of the lower lips so as to prevent the escape of flowing concrete and provide a bonding key for a subsequent coating.

7. A reenforced concrete column comprising 85 a tubular sheet metal shell, a concrete core and vertical reenforcing rods secured in said shell, said shell having elongated horizontal slits therein, the lower edges of the upper lips of said slits being positioned inwardly with respect to the upper edges of the lower lips thereof to form cups which 90 will retain the flowing concrete and form a key for a subsequent coating.

8. A reenforced concrete column comprising 95 a tubular sheet metal shell with a flaring end, a concrete core and vertical reenforcing rods secured in said shell, said shell having elongated horizontal slits therein, each lower lip being integral with the shell 100 at its ends and base and inclining upwardly and outwardly to form a pocket which will retain the flowing concrete and form a bonding key for a subsequent coating.

9. A combined form and reenforcing 105 member for concrete columns, comprising a tubular metal shell having horizontal slits therein, the lower edges of the upper lips of said slits being positioned inwardly with respect to the upper edges of the lower lips 110 thereof so as to form cups which will retain the flowing concrete and form a key for a subsequent coating.

10. A combined form and reenforcing member for concrete columns, comprising a 115 circumferentially continuous metal shell flaring at the end and having horizontal slits therein, the lower edges of the upper lips of said slits being positioned inwardly with respect to the upper edges of the lower lips 120 thereof.

11. A combined form and reenforcing member for a concrete column, comprising a circumferentially continuous tubular metal shell having horizontal slits therein, the 125 lower edges of the upper lips of said slits being positioned inwardly with respect to the upper edges of the lower lips thereof and metal rods secured lengthwise in said shell.

12. The process of making columns which 130

- 4
- consists in rolling a sheet of metal into cylindrical form, securing the edges thereof together to form a circumferentially continuous shell capable of resisting circumferential tension, erecting said shell in position, mounting thereon an inverted conical shell adapted to resist circumferential tension, filling said cylindrical and conical shells with concrete and coating the same with fireproofing material.
13. The process of making columns which consists in rolling a sheet of metal into cylindrical form, securing the edges thereof together to form a circumferentially continuous shell capable of resisting circumferential tension, erecting said shell in position, placing vertical reinforcing bars therein, mounting thereon an inverted conical shell adapted to resist circumferential tension, filling said cylindrical and conical shells with concrete and coating the same with fireproofing material.
14. The process of making a combined form and reinforcing member for concrete columns which consists in slitting a sheet of metal and rolling it into the form of a shell and joining the ends of said sheet together to form a circumferentially continuous shell, the slits being so designed and disposed that the slitted portion of said shell will be capable of resisting at least as much circumferential tension as said joint.
15. A combined form and reinforcing member for concrete columns, comprising a sheet of metal rolled into a circumferentially continuous tubular shell having a longitudinal seam, said shell having slits therein, said slits being so disposed that the circumferential tensile strength of the slitted shell is substantially equal to the tensile strength of the seam.

Signed at Buffalo, New York, this 31st day of May, 1919.

HERVEY E. BUTCHER.
